PILE FABRIC FLOOR COVERING

Ernest R. Kuepfer, Cornwall on the Hudson, N.Y., assignor to The Firth Carpet Company, Inc., New York, N.Y., a corporation of New York

Filed July 17, 1958, Ser. No. 51,815

Term of patent 14 years

(Cl. D92—4)

FIG. 1

Fig. 1 is a plan view of a pile fabric floor covering, showing my new design;

A design unit is enclosed within the dot and dash lines in Figure 1 which unit is repeated in regular succession as indicated by the extensions beyond the border unit boundaries.

I claim:

The ornamental design for a pile fabric floor covering, substantially as shown and described.
